UNITED STATES PATENT OFFICE.

JEROME M. GREEN, OF ROCHESTER, NEW YORK; PERRY S. DARROHN, ADMINISTRATOR OF SAID GREEN, DECEASED, ASSIGNOR TO RICHARD H. THURSTON, OF ELMIRA, NEW YORK.

ACETYLENE-GENERATOR.

SPECIFICATION forming part of Letters Patent No. 738,794, dated September 15, 1903.

Application filed October 25, 1900. Renewed July 17, 1903. Serial No. 166,049. (No model.)

To all whom it may concern:

Be it known that I, JEROME M. GREEN, of Rochester, in the county of Monroe and State of New York, have invented certain new and 5 useful Improvements in Acetylene-Generators; and I do hereby declare the following to be a full, clear, and exact description of the same, reference being had to the accompanying drawings, forming a part of this specification, and to the reference-numerals marked thereon.

My present invention has for its object to provide an improved generator to be employed for producing gas from calcium or other carbid and one that is adapted particularly for use upon railway-cars or similar vehicles where the generator is subjected to sudden jars or jolts tending to disturb the equilibrium of the water or other liquid employed to act upon 20 the carbid.

The further object of my invention is to control the action of the liquid upon the carbid whereby the gas may be produced slowly at an even pressure and without unduly increasing the temperature of the parts of the 25 generator and also to provide means for preventing the splashing or formation of waves in the liquid as the generator is agitated.

To these ends my invention consists in certain improvements in construction and combination of parts, all as will be described, and the novel features pointed out in the claims at the end of this specification.

In the drawings, Figure 1 is a vertical sectional view through a generator constructed in accordance with my invention. Fig. 2 is a similar view taken at right angles to that of Fig. 1. Fig. 3 is a horizontal sectional view on the line 3 3 of Fig. 2. Fig. 4 is a sectional view on the line 4 4 of Fig. 1. Fig. 5 is a similar view on the line 5 5 of Fig. 1. Fig. 6 is a sectional view of a supplemental generating-box, and Fig. 7 is a sectional view of the receiving or storage tank.

Similar reference-numerals in the several figures indicate similar parts.

Generators constructed in accordance with my invention embody generally an outer casing open at its upper end, having the sides 50 1 and the bottom 2, an inner casing embody-

ing the sides 3 and top 4, and an inclosed generating-chamber, the latter open at its lower end, having the sides 6 and top 7, through which latter pass bolts 8, securing the chamber within the inner casing and supporting 55 the former with its sides 6 above the lower edges of the latter. A suitable gas-pipe 9, leading from the side of the generating-chamber below its top, passes to the exterior of the generator and is connected to a gasometer or reservoir, to be presently described, and a suitable valve 10 is employed for closing the said pipe when desired.

The carbid is adapted to be supported in the generating-chamber, and the action of the 65 water thereon is controlled by the pressure of the gas in the chamber, and to accomplish these objects I provide a support in the form of a tubular shell constructed in two sections 11 and 12, the former (lower) section being 70 adapted to rest upon the bottom 2 of the outer casing, small lugs or projections 13 being provided to center it, and the latter (upper) section is somewhat smaller in diameter and separated from the lower section, as 75 shown, being held by supporting-pieces 14. A series of supporting wires or bars 15, extending across the lower section 11 near its top and arranged at a slight angle to the horizontal, so that one side of the mass of 80 carbid will be lower than the rest, permitting the liquid as it runs in the chamber to contact with but a small portion thereof, and at the ends of the bars are apertures 16 to allow the entrance of the liquid as it rises upon 85 the outside of the support, as will be presently described. Below the carbid-support is arranged a device for preventing the splashing or slopping of the liquid from side to side, arranged loosely upon supports 17 90 and consisting of a band of flat spring metal 18, bent into the form of a spiral. It will be readily seen that any sudden movement of the liquid sidewise will be resisted by the coils of the spiral band which are free to 95 move from side to side of the center of the chamber, permitting the several convolutions to be moved closer together, forming a series of narrow passages upon the side of the chamber where the pressure of upward current of 100

the liquid is the greatest, thereby increasing the friction upon the latter and successfully preventing a wave motion upon the surface thereof.

5 When during the operation of the machine the water-level is above the spiral and in proximity to the carbid, if the generator is sufficiently agitated to cause a wave the edges of the latter will simply wash over the 10 upper edge of the casing 11, the upper section 12 being separated therefrom and smaller in diameter to prevent the liquid forming the wave from contacting therewith. Stationary plates or partitions might be employed in 15 lieu of the spiral spring band; but I prefer to use the device described, as I am enabled to space the supporting-bars for the carbid farther apart to allow the ashes or hydrated lime from the carbid to readily drop away, 20 the smaller pieces of the unslaked carbid which may drop through the bars will be arrested upon the closer-wound edges of the spiral until entirely reduced, and the slight vibrating movement of the latter as the water strikes against it also tends to prevent 25 the deposit of any ashes thereon. Provided in the lower end of the section 11 are a series of apertures 19, arranged with their lower edges somewhat above the bottom of the section, and provided upon the exterior of the latter are valves or doors 20, hinged to the section at their upper edges and adapted to normally close the apertures against the inward movement of the liquid, though free to 30 move outwardly as the gas expels the water from the chamber, carrying with it the ashes from the decomposed carbid.

When in operation, the parts of the generator are arranged as shown, and the inner 40 casing is secured within the outer one by means of a bar 21, secured at its opposite ends by nuts 22 on the threaded ends of bolts 23, secured to the outer casing. In the top 4 of the inner casing I provide an opening normally closed by a screw-plug 24, through 45 which the liquid may be supplied to the generator, and in the present construction of my device I am enabled to arrange my casing of a suitable size relative to the quantity of gas 50 to be produced, whereby all the liquid that is necessary to reduce the given quantity of carbid and also produce the required pressure on the gas may be introduced into the casing at one time, thereby obviating the necessity of employing a separate liquid-feeding apparatus, and by my arrangement of the device the pressure of the gas is not materially affected by the reduction in the volume of the liquid. The generating-chamber 55 is preferably arranged upon one side of the inner casing, and a portion of the latter at one side of the chamber is partitioned off by the curved partition 25 and the crescent-shaped top and bottom portions 26 and 27, the former 60 being arranged upon a line with the top 7 of the generating-chamber and the latter located near the bottom edge thereof, provid-

ing a broad space for the liquid and residue from the carbid at the bottom of the generator and narrowing the passages at the side of the chamber, thereby reducing the vertically-extending column of liquid and its compressional force upon the gas. As the liquid is forced upward by the gas it is allowed to flow over the top 7 of the chamber and the top 26, 75 and arranged between these and the top 4 of the inner casing are plates 27' and 28, provided with apertures in their lower edges, adapted to prevent the free movement of liquid from side to side, and apertures 29 in the upper edges of the plates allow the air or gas contained therein to escape and pass out through an open vent or pipe 30.

In order to arrest the rotary movement of the liquid between the inner and outer sections, radially-extending plates or partitions 31 are arranged upon the former, and upon the outer side of the lower section 11 of the carbid-support I also arrange similar plates 32, as shown in Figs. 3 and 5. By leaving 80 the space between the inner and outer sections of the generator open at the top the atmospheric pressure upon the liquid in the generator is always constant, and I do not necessarily rely upon the vent 30 to accomplish this purpose and insure a steadiness in the flame at the burner when the generator is jolted or subjected to a sudden movement in a vertical direction, as would otherwise be the case. 33 indicates a pipe arranged at the 90 side of the generating-chamber and extending in proximity to the top of the inner section, where it is provided with an aperture 34, a similar aperture or V-shaped notch 35 being arranged at its lower end and extending upwardly slightly above the lower edge of the generator-casing to permit the escape of the air contained therein upon first starting the generator, as will be explained. In Fig. 6 I have shown a supplemental generating device in the form of a box 40, having the cover 41, each of said parts being provided with a minute aperture 42, through which the liquid is admitted slowly to a small piece of carbid placed therein.

In Fig. 7 I have shown a reservoir consisting of a tank 50, adapted to be placed at the side of the generator into which the gas is conducted by the pipe 9, any suitable form of detachable connection being employed to 100 permit the inner casing of the generator to be removed when the device is recharged, or, as the reservoir is comparatively small, it may be rigidly attached to the inner casing and elevated with the latter when it is removed. 105 A drainage-cock (not shown) is arranged in the side of the casing to allow the water to be drawn off and to maintain its proper level above the end of the pipe 9. 43 indicates a conical-shaped dash-plate secured at the sides 110 to the interior of the reservoir at the water-level and provided at its top with an aperture 44, and around its edges are a series of apertures 45. The conical formation of the

plate prevents any excessive wave motion on the surface of the water from jarring or shaking of the device, which might uncover the discharge-orifice. By arranging the end of 5 the pipe only slightly below the surface of the water the pressure in the gas chamber and reservoir is more nearly equal, and the gas will be allowed to flow from the former into the latter without a sudden reduction of the 10 pressure in said chamber, while the check-valve formed by the liquid will maintain the pressure in the reservoir, and by admitting the gas in a horizontal line near the surface of the liquid the latter will be circulated in 15 the reservoir and the gas more thoroughly washed.

In operating the generator the parts are assembled as shown in Fig. 2, with the carbid supported upon the bars 15, as shown, and 20 the box 40, having the carbid therein, located in the bottom of the section 11. The water or other liquid is then introduced in the proper quantity into the generator through the supply-aperture in the top 4 of the inner section 25 and flowing downward works its way beneath the section 11 and as it rises therein first enters the box 40 through one of the apertures 42 and contacting with the carbid therein immediately generates gas, which as it rises in 30 the chamber 6 will begin to expel the air therein, and as the valve 10 in the pipe 9 has been previously closed the mixed air and gas will pass upward through the pipe 33 above the level of the liquid and to the exterior of the 35 casing through the vent 30. By inclosing the carbid employed for this purpose in a separate box the generation of the gas is slow and somewhat under control, and the gas being lighter and warmer than the air it rises to the 40 top of the chamber, expelling the air from the generating-chamber without subjecting any portion of the mass of carbid to the action of the liquid, and the pressure of the gas previously generated is sufficient to hold the liquid 45 outside of the chamber 6. When a further supply of gas is desired, the valve 10 may be opened, when the reduced pressure in the generating-chamber will permit the liquid to rise therein and contact with the mass of carbid to produce the gas as rapidly as it is required, and any excess of gas will expel the liquid from the chamber.

The downward and outward movement of the liquid as it is forced outward through the 50 apertures 19 carries with it the ashes or hydrated lime, and the check-valves or doors 20, closing and forming a check against its inward movement, causes the sediment to be deposited around the edges of the outer section, and the free entrance of the liquid being prevented by the valves the liquid only enters the casing through the apertures 16 as it rises in the narrow passages between the section and the sides 6 of the generating-chamber. This flowing of the liquid causes currents therein, so that the heated liquid which 55 is expelled each time the carbid is acted upon

is thoroughly cooled and mixed with the remaining liquid before it again enters the generating-chamber. The cool liquid only being permitted to act upon the carbid, cooler gas is produced than would otherwise be the result, and by arranging the parts so that the surrounding liquid forms a comparatively short and narrow vertical column I am enabled to maintain an even pressure upon the gas. The enlarged space at the bottom of the casing affords ample room in which to accommodate the residue from the decomposed carbid, and the corresponding space in the upper end of the inner section above the generating-chamber and plate 26 permits me to employ a comparatively large supply of liquid without materially increasing the height of the vertical column to affect the gas-pressure. The liquid being free to flow over the top of the generating-chamber, the latter is prevented from becoming heated, and the perforated partitions or walls 27 28 prevent an undue movement of the liquid in the casing. 70 75 80 85 90

It will be noted that the gas-passage 9 from the generating-chamber passes out below the upper end thereof and that the upper end of the upper section of the carbid-holder is below the top of said chamber, so that the gas 95 is necessarily brought in contact with cool metal surfaces before it passes out of the chamber and also afterward in the pipe 9 and any moisture condensed.

The construction of the carbid-holder is 100 such that the liquid is prevented from splashing upon the carbid when the generator is agitated, this result being accomplished partly by the spiral or involute spring in the bottom, and while I prefer that this device be of spring 105 material and in the shape shown its principal feature is that it is, in effect, a series of vertically-extending plates, which to some extent are movable relatively to the sides of the casing and to each other. 110

Generators constructed in accordance with my invention are self-regulating, and it is only necessary to supply the carbid and liquid in sufficient quantities to obtain excellent results. The device is simple in construction, and the arrangement of parts described prevents the excessive movement of the liquid and its action upon the carbid, making it particularly adapted for use upon railway-cars, vehicles, or in similar places where it is 120 constantly subjected to forces tending to disturb the normal position of the liquid. 115 125

I claim as my invention--

1. In a generator the combination with an outer section, adapted to contain a liquid, an inner section arranged in the former and open at its lower end, and a generating-chamber located in the latter, of a carbid-holder arranged in the generating-chamber, embodying a lower tubular section having the open 130 carbid-support and a similar separate section above the latter, and a gas-passage leading from the said chamber. 125

2. In a generator the combination with an

outer section adapted to contain a liquid, an inner section arranged in the former and open at its lower end, a generating-chamber having the open lower end, and the gas-pipe leading 5 from the chamber, of a carbid-holder contained in the generating-chamber, embodying the lower section having the carbid-support and the upper section smaller in diameter than the former arranged above the said sup- 10 port.

3. In a generator the combination with an outer casing adapted to contain a liquid, an inner section open at the lower end, a generating-chamber located in the latter having 15 the lower open end, and the gas-pipe leading therefrom, of the removable carbid-holder fitting within the chamber having the carbid-support and provided with apertures arranged in proximity to the support, and ver- 20 tically-extending wings or flanges on the holder forming narrow passages between the latter and the sides of the chamber.

4. In a generator the combination with an outer section adapted to contain a liquid, an 25 inner section therein open at its lower end, a generating-chamber having the lower open end, and a gas-pipe leading from the chamber, of a carbid-holder located within the chamber and having a carbid-support and open above 30 the support and having apertures in its sides near the lower edges, and valves for closing the apertures and permitting the passage of liquid through them in but one direction.

5. In a generator the combination with an outer section adapted to contain a liquid, an 35 inner section open at its lower end, and a gas-chamber having an outlet-passage, of a car- 40 bid-holder within the lower end of the chamber having wings upon the exterior form- 45 ing with the chamber-walls narrow passages and provided with the apertures near the upper ends of said passages, and apertures ar- 50 ranged in the lower end of the holder and valve therefor.

45 6. In a generator the combination with an outer section adapted to contain a liquid, an inner section provided therein open at its lower end, and the generating-chamber in the latter section having the lower open end sup- 55 ported above the bottom of the outer section, of a carbid-holder open at the upper end having the outer wall extending into the lower end of the chamber, the radially-extending wings thereon forming the separate passages between the proximate faces of the walls, and the valves located in the side of the carbid- 60 holder operating to permit the passage of the liquid in one direction only relatively to the carbid.

60 7. In a generator the combination with an outer casing containing a liquid, an inner cas- 65 ing having the open bottom arranged therein, and a generating-chamber located in the latter casing open at the lower end and having the gas-outlet passage, of a carbid-holder em- 70 bodying a shell, adapted to fit within the

chamber having a support for the carbid near its upper portion and provided with apertures for the passage of the liquid, and de- 75 vices forming a series of open liquid-pas- 80 sages beneath the carbid-support.

8. In a generator the combination with an outer casing containing a liquid, an inner cas- 85 ing open upon its lower end, a generating-chamber having the open bottom and ar- 90 ranged in the casing with narrow vertical liquid-passages at its sides terminating in en- 95 larged chambers at their ends, of a carbid- 100 holder embodying a shell or casing within the generating-chamber and means for sup- 105 porting the carbid, passages between the ad- 110 jacent walls of the support and chamber and means for controlling the horizontal move- 115 ment of the liquid in the carbid-holder be- 120 neath the support.

9. In a generator the combination with a casing containing a liquid, an inner section arranged therein having the open bottom, a gas-generating chamber open at the lower end arranged in the latter section, and the 95 narrow passages for the liquid surrounding the chamber communicating at their ends with enlarged liquid-chambers extending upon opposite ends of the generating-cham- 100 ber, of a holder for the carbid arranged in the chamber having the carbid-support and provided with passages for the liquid and means arranged beneath the support for controlling the horizontal movement of the liquid.

10. In a generator the combination with a 105 casing containing a liquid, an inner section provided therein having the open lower end, a generating-chamber arranged in the latter open at its lower end and having the top located below that of the inner section, the 110 narrow passage surrounding the chamber connecting the larger spaces at the ends thereof and perforated partitions arranged in space at the top of the section, of the carbid- 115 support located in chamber, and means pro- 120 vided in the holder for controlling the horizontal movement of the liquid therein.

11. In a generator the combination with a 125 casing containing a liquid, an inner section contained therein open at the lower end, and a generating-chamber arranged in the latter section having the lower open end, of a car- 130 bid-holder embodying a shell or casing adapt- 135 ed to fit within the chamber having the car- 140 bid-support and a shell separated from the casing and mounted thereon above the sup- 145 port, and inlet and outlet passages for the liquid in the holder.

12. In a generator the combination with a 150 casing containing a liquid, an inner section provided therein open at the lower end, and a generating-chamber arranged in the latter having the lower open end, of a carbid-holder 155 embodying a shell or casing fitting loosely in the chamber having the carbid-support and a shell separated from the casing and mounted above the support, inlet-passages leading

- into the holder at its upper end and valved exit-passages for the liquid at the bottom of the holder.
13. In a generator the combination with a casing containing a liquid, an inner section therein open at the lower end, and a generating-chamber having the lower open end, of a shell or casing located in the generating-chamber provided with the carbid-support and having the apertures at its upper end near the support and the valved apertures at its lower end, the shell separated from the casing and held above the carbid-support and means arranged in the holder beneath the support for controlling the horizontal movement of the liquid in the holder.
14. In a generator the combination with an outer casing containing a liquid, an inner casing open at the bottom having the sides parallel with those of the outer casing and the wings or partitions between the proximate faces of said section, a generating-chamber open at the lower end, a narrow passage surrounding said chamber connecting the enlarged spaces in the inner section upon the opposite ends of the generating-chamber, and a perforated plate controlling the horizontal movement of the liquid in the top of the inner casing, of a carbid-holder arranged with in the generating-chamber forming vertical passages for the liquid between the adjacent sides of said chamber and holder, wings or partitions arranged between said parts and means located in the holder for controlling the horizontal movement of the liquid therein.
15. In an acetylene-generator the combination with a generating-chamber and a carbid-support therein arranged above the bottom, of vertically-extending plates located in the chamber beneath the carbid-support to control the lateral movement of liquid in the generating-chamber.
16. In an acetylene-generator, the combination with a generating-chamber and a carbid-support therein arranged above the bottom, of vertically-extending plates located in the chamber beneath the carbid-support and movable laterally relatively thereto to control the movement of liquid therein.
17. In an acetylene-generator, the combination with a generating-chamber and a carbid-support therein arranged above the bottom, of vertically-extending plates located in the chamber beneath the carbid-support to control the lateral movement of the liquid therein, 55 said plates being laterally movable relatively to each other and to the walls of the chamber to control the movement of the liquid.
18. In an acetylene-generator, the combination with a generating-chamber and a carbid-support therein arranged above the bottom of the chamber, of a horizontal spiral strip arranged in the chamber beneath the support with its convolutions capable of moving relatively to control the movement of the liquid. 60
19. In an acetylene-generator the combination with a generating-chamber and a carbid-support therein, of a spiral strip of spring material arranged in the chamber beneath the support with its convolutions capable of moving relatively and attached rigidly at one end. 70
20. In an acetylene-generator the combination with a generating-chamber, of a carbid-holder therein embodying a lower section and an upper section of relatively smaller diameter and slightly separated from the former, said lower section having a carbid-support below its upper end and one or more apertures in its sides. 75
21. In an acetylene-generator the combination with a generating-chamber, of a carbid-holder therein having a carbid-support above the bottom of the chamber and apertures in the sides at different levels and outwardly-opening valves for the lower apertures. 80
22. In an acetylene-generator the combination with a generating-chamber, of a carbid-holder having an open carbid-support, and apertures in the sides at different levels, outwardly-opening valves for the lower apertures and vertically-extending laterally-movable plates arranged beneath the support for controlling the movement of liquid. 85
23. In an acetylene-generator the combination with a generating-chamber, of a carbid-holder therein having an open carbid-support and openings at, above and below said support, outwardly-opening valves for the lowermost openings and the spirally-wound yielding plate in the holder below the carbid-support. 90
24. In an acetylene-generator the combination with a generating-chamber, of a carbid-holder therein having an open carbid-support and openings at, above and below said support, outwardly-opening valves for the lowermost openings and the spirally-wound yielding plate in the holder below the carbid-support. 100
